[57] **CLAIM**

The ornamental design for a handle for a beverage can, as shown and described.

DESCRIPTION

FIG. 1 is a top perspective view of a handle for a beverage can showing my new design, the beverage can being shown by broken lines for illustrative purposes only;

FIG. 2 is a front elevational view thereof, the rear view being a mirror image thereof;

FIG. 3 is a right side elevational view thereof;

FIG. 4 is a left side elevational view thereof; and

FIG. 5 is a top or bottom plan view thereof.
